UNITED STATES PATENT OFFICE

CHARLES A. BOREHAM, OF COALINGA, CALIFORNIA.

VEHICLE-SPRING.

1,108,424.

Specification of Letters Patent. Patented Aug. 25, 1914.

Application filed February 18, 1914. Serial No. 819,406.

To all whom it may concern:

Be it known that I, CHARLES A. BOREHAM, a citizen of the United States, residing at Coalinga, in the county of Fresno and State of California, have invented new and useful Improvements in Vehicle-Springs, of which the following is a specification.

The object of the present invention is to provide an elliptical spring of the multi-leaf type which shall be more durable, cheaper to manufacture and repair, and higher in efficiency, than springs of this class now generally employed.

In the accompanying drawing, Figure 1 is a side view of the spring; Fig. 2 is a vertical section thereof; Fig. 3 is a cross section thereof on the line 3-3 of Fig. 2.

Referring to the drawing, 1 indicates a housing, of an inverted channel shape in cross section, of which the central portion is horizontal and the terminal portions 2 extend upward outwardly. Contained within the central portion of said housing is the central portion of a multi-leaf elliptic spring. Each complete leaf of said spring is in two separate halves or sections 3, which, when nearly abutting, end to end, assume the form of a complete leaf spring. Said halves are held in the proper relation to each other and to the housing by the engagement with each other of concavo-convex indentations 4, in said leaf sections near their inner ends. The convex side of each indentation fits snugly within the concave side of the indentation of the next leaf section above. To clamp said leaf sections together I provide plates, namely, a lower plate 6 which has concavo-convex indentations 7, the convex sides of the indentations fitting in the concave sides of the indentations 4 of the sections of the longest and lowermost leaf, and a longer upper plate 8 contained within the housing, above the leaf sections and having in its under side concavities 9, into which fit the convex sides of the indentations of sections of the uppermost and shortest leaf. Said plate is formed in its under side near its ends with transverse grooves, in which are contained rubber cushions 10 resting upon said uppermost leaf. The plate 8 is maintained in position in the channel-shaped housing by a boss 11 projecting upwardly from the center of the plate 8 and extending through a hole in the central portion of the housing 1. Both of said plates, with the leaf spring sections therebetween,

are firmly clamped within the housing by means of a pair of U-bolts 12, extending around the housing and the lower plate, and through apertured ears 13 in a supporting plate 14, nuts 15 being screwed on said bolt ends above said ears.

I claim:

1. A leaf spring of the character described, comprising a series of two-part superposed resilient leaves, the inner ends of the two parts of each leaf being adjacent to each other, and the inner portion of each leaf section having a concavo-convex portion forming on one side a recess and on the other side a projection, said leaves being arranged with said concavo-convex portions interlocking, upper and lower plates between which said leaves are confined, said plates also having concavo-convex portions interlocking with the concavo-convex portions of the leaves, an inverted channel-shaped housing inclosing said leaves and plates, and means for clamping said leaves and plates within the housing.

2. A leaf spring of the character described, comprising a series of two-part superposed resilient leaves, the inner ends of the two parts of each leaf being adjacent to each other, and the inner portion of each leaf section having a concavo-convex portion forming on one side a recess and on the other side a projection, said leaves being arranged with said concavo-convex portions interlocking, upper and lower plates between which said leaves are confined, said plates also having concavo-convex portions interlocking with the concavo-convex portions of the leaves, an inverted channel-shaped housing inclosing said leaves and plates, the upper plate having an upward projection through a hole in the housing, and means for clamping said leaves and plates within the housing.

3. A leaf spring of the character described, comprising a series of two-part superposed resilient leaves, the inner ends of the two parts of each leaf being adjacent to each other, and the inner portion of each leaf section having a concavo-convex portion forming on one side a recess and on the other side a projection, said leaves being arranged with said concavo-convex portions interlocking, upper and lower plates between which said leaves are confined, said plates also having concavo-convex portions interlocking with the concavo-convex por-

tions of the leaves, an inverted channel-shaped housing inclosing said leaves and plates, a supporting plate above the housing having laterally projecting ears, U-bolts 5 circling the housing and the plates and leaves therewithin, and extending through said ears, and nuts on said bolts.

In testimony whereof I have hereunto set my hand in the presence of two subscribing witnesses.

CHARLES A. BOREHAM.
